UNITED STATES PATENT OFFICE.

SERAPHINE F. BAUWENS, OF CHICAGO, ILLINOIS, ASSIGNOR, BY MESNE ASSIGNMENTS, TO WIREBOUNDS PATENTS COMPANY, OF KITTERY, MAINE, A CORPORATION OF MAINE.

WIRE-BOUND-BOX MACHINE.

1,315,855.

Specification of Letters Patent. Patented Aug. 19, 1919.

Application filed September 25, 1914. Serial No. 863,421.

To all whom it may concern:

Be it known that I, SERAPHINE F. BAUWENS, a citizen of the United States, residing at Chicago, in the county of Cook and 5 State of Illinois, have invented a certain new and useful Improvement in Wire-Bound-Box Machines, of which the following is a specification.

This invention relates to machines for use 10 in making wirebound boxes by the action of binding wire applying and stapling or fastener-setting mechanism upon assembled box parts, such for example as the assembled side sheets and cleats composing the sections of a 15 wirebound box blank.

Among other objects the invention is intended to provide improved mechanism for controllably disposing the fasteners or staples by which the box materials are secured 20 together and the binding wires connected thereto; also to provide various improvements, as hereinafter described and claimed, contributing to the efficiency of operation of such machines. Among these are improvements in the general organization of the machine, in the details of particular work-supporting and feeding means, and in regulation and control of the feed mechanism whereby the work is progressively subjected 25 to the action of the stapling mechanism.

The invention will be best understood from the following description taken in connection with the accompanying illustration of one form of machine containing one 30 specific embodiment of my invention, and its scope will be particularly set forth in the claims.

While the device of this invention is capable of use upon many different shapes of 35 wire bound boxes or packages or other articles, its primary use is in the construction of substantially rectangular, though not necessarily square, boxes and accordingly the preferred form of the machine set forth in 40 the drawings is illustrated and will be, for convenience, described as used in making a box of this character.

In the drawings,

Figure 1 is a fragmentary plan view of an 45 approved type of box blank machine embodying my invention, showing such parts as are necessary for illustration of the invention.

Fig. 2 is a side elevation partially in section of the machine illustrated in Fig. 1. 55

Fig. 3 is an end view also partially in section taken at the right hand end of Figs. 1 and 2.

Fig. 4 is a detail changed position view of a part of the device which will be more 60 fully described hereafter.

Fig. 5 is an end view of the device taken from the left hand end of Figs. 1 and 2.

Fig. 6 is an enlarged detail view of the shock absorbing mechanism. 65

Fig. 7 is a sectional view at right angles to Fig. 1, showing the wire cutting mechanism which appears upon the front and upper portion of Fig. 5.

Fig. 8 is a face view of this cut off mechanism taken from the left hand side of Fig. 7, it being a slightly enlarged and partially 70 sectional view of the same parts which appear in the upper half of Fig. 5.

Fig. 9 is a detail plan view of one of the 75 sprocket chains removed from the machine.

The machine is carried upon a suitable frame work which may take a variety of forms, but which in the particular case here illustrated takes the form of two parallel 80 side frames made up of three separate parts 12, 13 and 14 connected together, said side frames being spaced apart by the rigid stationary separated bars 16 and 18 as well as other parts such as shafts and the like connecting them which will be hereafter referred to. For convenience, that portion of the machine including the side frame portion 12 and its connecting spacing member, will 85 be referred to as the operating head. 90

Journalized at a suitable point in the operating head is a shaft 20 having rigidly secured thereto by any suitable means two sprocket wheels 22 and 24 identical so far as their sprocket chain carrying ability is 95 concerned.

Similarly journalized at the opposite end of the machine in the support 14 is a shaft 26 carrying two sprocket wheels 28, one lying in the vertical plane of sprocket wheel 22, 100 the other in the plane of sprocket wheel 24. Over one sprocket wheel 24 and its opposite sprocket wheel 28 the sprocket chain 30 passes while over the second sprocket wheel 22 and its opposite wheel 28 the sprocket 105 chain 32 passes. These chains are alike as

cept that they are rights and lefts, as clearly shown in Fig. 3. Each chain consists in a plurality of relatively long links made up of a relatively narrow bar 34 and a relatively wide bar 36 having extending from its side a T or other shaped lug 38 designed for the purpose of having certain parts which will be hereafter described selectively secured. These links just described are pivoted at their ends by rivets to the shorter and deeper intermediate links 42.

The longitudinal members 13 of the side frames are of the cross section shown in Fig. 3 so as to form a horizontal track 44 on which the long links of the chains 30 and 32 rest and travel from sprocket to sprocket and these tracks 44 are provided with central recesses 46 in which the short links 42 of the chains travel, thus preventing longitudinal movement of the chain off from the tracks 44 as the chains progress through these members 13.

Rigidly secured to the vertical walls of the side members 13 (Fig. 3) by suitable devices, such as the screws 48, are angle irons 50 forming a horizontal and rigid track along the members 13 for the travel of the box cleats 52; that is to say, these angle irons form an independent track through each of the side members 13 above and clear of the tracks 44 and the sprocket chains thereon over which the box cleats 52 can be and are driven by adjustable devices which will be hereafter described.

Suitably mounted in the operating head is main drive shaft 54 propelled by any suitable source of power, not shown, conveyed to this shaft through a clutch pulley 56, (Fig. 5), manually operated in the ordinary manner by the hand lever 58 and automatically operated to shut off the power in the manner hereafter described by the cam 60 engaging a roller 62 on rod 64 connected with hand lever 58.

Rigidly secured to the main drive shaft 54, (see Fig. 2), by any suitable means is a heart-shaped cam 66 and an eccentric 68. Operated by this eccentric is a connecting rod 70 pivotally connected at 72 to a rocker arm 74 rigidly connected to a shaft 76 suitably mounted transversely of the machine. Rigidly connected to this shaft 76 as clearly shown in Fig. 3, are L shaped arms 78 arranged as right and left on which are pivotally mounted the push rods 80 pressed downward by the springs 82 and provided with rough teeth 84 for engaging and positioning the box sides in the manner which will more fully appear hereafter.

Pivotaly mounted upon a suitable cross rod or shaft 86, (Fig. 2), through the operating head is a rocker arm or lever 90 carrying a roller 92 traveling upon the heart shaped cam 66. Rigidly attached to the shaft 20 at any convenient point is a brake

wheel 94 having upon its circumference a brake band 96 whose opposite ends are connected at 98 and 100 to a short lever 102 suitably pivoted on the frame and rockable by a lever 104 which is in turn connected by 70 the rod 105 to the rocker arm 90. It will be seen that when the rocker arm 90 is pushed to the left by the heart shaped cam 66 the movement of the short lever 102 tends to bind the brake band 96 about the brake 75 wheel and lock it, and that movement in the opposite direction of the parts named tends to release this brake band. In practice, the parts are so proportioned and adjusted that this brake band seriously grips 80 the brake wheel 94 only when the extreme tip portion 106 of heart shaped cam 66 engages the roller 92 and at other times the brake wheel 94 runs freely inside the brake band. The proportion of the lever 102 to 85 the other parts is such that this gripping action, when the tip 106 of cam 66 passes roller 92, takes place very sharply and strongly, thereby positively stopping the shaft 20 at this time. This mechanism is de- 90 signed to bring the endless sprocket chains and the parts which they propel to a sudden and positive stop at desired intervals, as will hereafter more fully appear.

Also rigidly connected to the shaft 20 by 95 any suitable means is a ratchet wheel 110 whose teeth are adapted to be selectively engaged by at least one of a plurality of dogs 112 suitably pivotally mounted upon a head 114 of a rocker arm 116 journaled loosely 100 upon shaft 20 and reciprocated by a rod 118 connected to rocker arm 90. The result of this construction is that whenever rocker arm 90 is moved to the left by the heart shaped cam 66 some one of the dogs 112 is 105 engaged with the surface of the wheel 110 and therefore the wheel and consequently the shaft 20 is rotated to the left. When, however, heart shaped cam 66 has passed its tip 106 over wheel 92 permitting spring 120 110 to move arm 90 to the right the teeth 112 click idly over the ratchet teeth of wheel 110. From the foregoing it will be apparent that movement of rocker arm 90 to the left positively drives the shaft 20 and attached parts in a counter clockwise direction a given predetermined distance and that on the instant this movement of the rocker arm 90 and consequently of the shaft 20 ceases the brake device grips the brake 120 wheel 94 and prevents any over-movement or overslash of any of the parts.

Rigidly mounted upon cross member 18 of the frame, as best seen in Figs. 1 and 6, and with its center in the same vertical 125 plane as the arm 90 and the rod 118, heretofore described, is a longitudinal rack 126 rigidly secured in position by bolts or screws 128. Slidably mounted with reference to this rack is a cross head 130 made up 130

of two parallel side plates connected together by intervening spacing members which include the bolts or screws 132, 134 and 136. Bolt 132 acts as a bearing for connecting rod 138 whose opposite end is attached at 140 to the head 114 of rocker arm 116, from which it follows that this cross head 130 is reciprocated lengthwise of rack 126 as rocker arm 90 is reciprocated, as hereinbefore described. Journalized upon bolt 136, heretofore described, are a plurality of ratchet dogs 142, 143, 144 and 145 (Fig. 1) of different lengths so that at least one of them will always be sure to drop into and engage an adjacent tooth of rack 126 without any material lost motion. Bolt 134 carries a plurality of springs 146 adapted to normally press the ratchet dogs toward the teeth of rack 126. It will be seen that when any one of the teeth 142-145 is in engagement with rack 126, movement of rocker arm 90 to the right as viewed in Fig. 2 is prevented; that is to say, by one of these teeth 142-145 dropping into a tooth of rack 126, the point of steppage of the movement of the arm 90 in moving to the right as viewed in Fig. 2 is absolutely determined and consequently the point of its beginning and consequently the point of its beginning its next movement to the left with reference to its rotation of shaft 20 and consequently its movement of the endless sprocket chains is thereby determined.

The dropping of the latch dogs 142-145 is determined by the operation of a shaft 148 (see Fig. 6) journalized in the cross head 130 and extending beneath these dogs. In the particular case here illustrated, this shaft is provided with a notch 150 engaged by corresponding notches or other cam faces on the underside of the dogs 142-145 so that when these parts just mentioned are in register with each other the dogs drop into the rack teeth, whereas when the shaft is rotated so that they are not in register with each other; *i. e.*, the position of Fig. 6, the latch dogs are held off from the rack. Any form of sharply acting cam structure well known in the art which will take care of this control of these dogs in the manner described may be used without departing from this invention. On the outer end of shaft 148 is an arm or dog 152 engaged by spring 154 so designed as to hold this dog and consequently the shaft 148 in the position shown in Fig. 6 wherein the latch dogs 142-145 are held clear of rack 126.

Whenever the movement of the rocker arm 90 moves this cross head to the right until latch dog 152 strikes a pin 160 whose other functions will be hereafter described, this latch dog 152 travels over the surface of the pin thus rotating 148 in a counter clockwise direction to the position in which the cam devices carried by the shaft allows the dogs 142-145 to drop into the rack 126, in

other words, engagement of latch dog 152 with pin 160 instantly stops the cross head and consequently the arm 90 and attached parts at the point where this pin 160 is placed in the manner and for the purposes hereafter set forth. When, in further operation of the machine, the arm 90 moves to the left thereby moving both the cross head 130 and this pin 160 which is carried by the sprocket chain to the point where the chain is stopped in the manner described heretofore, the difference in radius of the chain links and the pivot 140 about the center of shaft 20 is sufficient to cause the cross head 130 to move a slightly less horizontal distance to the left than does the pin 160; in other words, the pin 160 moves with reference to the latch dog 152 under that dog and to the left just sufficiently so that it does not engage this latch dog 152, and when the points of the dogs 142-145 reach and pass over a slight elevation 162 at the end of the rack teeth proper thereby throwing the dogs up to a position where the shaft 148 is free to rotate under the action of spring 154, that shaft does rotate to the position where its cam surface engages the ratchet dogs 142-145 to hold them up in the position shown in Fig. 6, which position they remain in during the return stroke of arm 90 until the latch dog 152 strikes another pin 160 placed at another point on the sprocket chain where it is desired to again arrest the movement of the arm 90 and attached parts.

As heretofore described, the sprocket chains 32 are endless and may be of any length. In practice, it is desirable to have these chains of such a length that they will, in the course of one complete passage through the machine, take care of at least two complete box blanks of four sides each. The chains are divided up by push members which will be hereafter described carrying the pins 160, heretofore referred to, into a given number of box blank sections spaced as nearly as practical the same distance apart between successive box sections. In Fig. 1 the push members and the cleats for one such complete box blank are shown, there being five push members for each box blank comprising a front push member 164, a rear push member 168 and three intermediate push members 170.

All of the push members are alike in that they have a similarly shaped body portion 172 provided with a gripping jaw 174 controlled by a screw 176 so that they may be adjustably clamped on the T shaped lug 38 heretofore referred to on the side of the chain, and the screws 176 are selectively insertible in different holes in the upper surface of the push member thereby allowing for adjustment of the push members even up to a point where they partially project 120

over the ends of the longer links of the chain. Each one of these push members on the chain which runs adjacent to the operating mechanism of the machine, (the front 5 one as viewed in Fig. 1,) carries one of the pins 180. The push members upon the opposite chain do not need this pin except that the front push member is there provided with a corresponding pin 180 whose functions 10 will be hereafter described.

All of the push members on both chains have projecting from them push pins 182 which project into the path of travel of and engage the box cleats 52, heretofore described, with the result that each one of these push pins engages the adjacent box cleat traveling through the machine and forces it along the track provided for it on an angle iron 50, heretofore described. In 15 order to readily insert these cleats on this track, these push members and consequently the push pins 182 are spaced farther apart lengthwise of the chain than the lengths of the cleats and their ultimate positions with 20 reference to each other require. Each cleat 25 is pushed up against one of these pins by the spring tension mechanism 234 hereafter described.

Rigidly extending vertically from each 30 front push member is a finger or lug 184 and correspondingly placed upon each rear push member is a similar rigid finger 186. Pivoted mounted upon the side of each 35 of the intermediate push members is a vertical finger 188 whose rotation in a vertical plane is limited by the pins 190 (see Figs. 2 and 4). This construction allows a limited movement of these vertical fingers so as to permit slight variations in the widths 40 of the box sides which, in the manner well known in the art, are placed across the sprocket chains over corresponding cleats and between these fingers on successive push members. As the placing of these box sides 45 is well known in the art, only one box side 192, is shown in dotted lines in Fig. 2 so placed.

Referring to Figs. 5, 7 and 8, the bar 16 of the frame has rigidly attached to it by 50 screws 194 two bracket members 196, one above each of the sprocket chains of the machine, in which is pivoted by means of the cylindrical members 198 the longitudinal bar 200 whereby this bar 200 is rotatable on 55 its own axis. Hooked over this bar 200 are two wire cut-off machines 202, well known in the art, one for each sprocket chain. These cut-off machines are provided with shear members 204 operated by the combined action 60 of the spring 206 and the depressible rod 208, in the ordinary manner. Reciprocably mounted in suitable slots 209 cut in the operating head is the horizontal bar 210 driven by connecting rods 212 operated by eccentric 65 214 on the main drive shaft 54, the

result being that when projecting brackets 216 on this bar 210 are thus brought in contact with the upper ends of rods 208 the cut-off shears 204 are operated.

As this bar 210 reciprocates at each revolution of the main shaft and as the action of the cut-off shears is only required intermittently, the time of operation of the cut-off shears is regulated by swinging the cut-off mechanism so that the ends of the bars 70 208 are only in the path of travel of these brackets 216 when it is desired to have cutting effected by the shears 204. This tilting of the shearing mechanism is made possible by the fact of their being mounted 80 upon the rotatable bar 200, and the rocking motion is effected automatically by the following mechanism: Rigidly connected to and extending from the bar 200 at any suitable point is a short arm 218 having adjustably connected to it a connecting rod 220 whose opposite end is pivoted at 222 to the shorter arm 224 of a bell crank mounted on shaft 226 whose longer arm 228 is engaged by the pin 180 carried by the front 90 push member on the rear chain, as heretofore described. Pin 180 operates both arm 228 to control the cutting mechanism and also the shaft to control the throw out clutch. 95

Fig. 8 shows the shears in operative position, while Fig. 2 shows the same in inoperative position.

Wire is supplied to the machine by mechanism well known in the art, and therefore not here shown, so as to pass under the standard, well-known, prior art stapling mechanism 230 also operated by the reciprocating bar 210 and thence under the cut-off shears 204. Were the wire not severed successive complete box sections delivered 100 by the machine would be connected by the wires with resulting tangling and other confusion in handling the product of the machine which, in prior machines, has been taken care of by clipping the wires by hand 105 as each complete box blank comes out of the machine. In this machine when one complete box blank has been delivered from the machine and another box blank is about to be formed and preferably after one or two 110 staples have been driven in the front cleats of the next box blank, shown at the left of Fig. 1, and across the wire thereon so as to prevent the ends of the wire getting loose and therefore out of control of the machine, the pin 180 on the front push member of the now entering box blank engages arm 228 and thus swings the cut-off mechanism to position under the brackets 216 whereupon on the next descent of these 115 brackets, they strike the upper ends of the rods 208 and thus force the cutting jaws 204 to sever the wires, one on each side. The cut off mechanism is returned to normal 120 position by the spring 400. 125 130 135 140 145 150 155 160 165 170 175 180 185 190 195 200 205 210 215 220 225 230 235 240 245 250 255 260 265 270 275 If more than two wires are to be applied to the given box, it is only necessary to hang additional cut-off machines upon the bar 200, placing them so that their cutting jaws are over the intermediate wires of the box which they are to take care of.

In order that the box cleats may be accurately positioned with the ends of the box sides and that the box may be of a uniform standard length, it is necessary that the opposite outer edges of the cleats passing through the machine be the same distance apart at the time stapling of the cleats, box sides and wires together takes place. In this machine, this is accomplished by providing slidable spring pressed push members 234 having upwardly extending fingers 232 and controlled by the springs 236 adapted to automatically press the cleat member which is being stapled against the adjacent side wall of the side frame member 13, as clearly appears in Fig. 1. This last described mechanism also serves the function of retarding the longitudinal movement of the forward cleats shown in Fig. 1 so that they are only moved to the left in Fig. 1 when and as engaged by the push pins 182, with the result that these forward or left hand cleats as viewed in Fig. 1 can never be in any but the correct position for stapling because the stapling operation in so far as driving staples at or adjacent to the ends of the cleats which is one of the important functions of this machine is concerned, is controlled by the pins 160 which are always in fixed relation to the pins 182.

Pivoted on a suitable bolt 240 (Figs. 1 and 3) is a plate 242 having in its upper face a notch 244 lying in the same horizontal plane as the pins 160 on the push member. This plate is normally held up by a spring of any construction, not shown in detail, so that this notch in the plate is normally, when in the position described, in the path of dog 152 to trip the ratchet dogs 142-145 and thus stop the movement to the right of arm 90 and attached parts under the further action of spring 120. This plate is also so shaped that when one of the pins 160 moves over it, the plate gets out of the way and does not therefore exert any tripping action on ratchet dogs 142-145. If it were desired to staple the cleats only at distances apart represented by the movement of the machine due to a complete revolution of the drive shaft 54, except as varied by the action of the pins 160, this plate device 240-242 could be wholly omitted from the machine without in any way affecting the device. It is introduced so as to provide for stapling at regular short intervals, as for instance two inches apart except as varied by the pins 160 as will perhaps more fully appear when the complete operation of the whole device is given.

The arm 228 heretofore described is on shaft 226, on which cam 60 heretofore referred to is located if desired, with the result that when the machine is operated by a single workman and it is necessary for him to stop the machine every time the material for a full box blank has worked through the machine this stopping of the machine is automatically effected by the operation of this shaft 226 and the cam 60 controlling the hand lever 58 in the manner heretofore described. If a plurality of workmen are employed about the machine so that continuous operation is possible the cam 60 may be either wholly omitted or arranged by well known means to be thrown out of effective operation.

Operation.

Assume that the machine is in the position shown in the drawings with the cleats for a complete box in such position; that the box sides, not shown in the drawings, are placed over them; that the wire, not shown in the drawings, is in position ready to be attached; that the automatic stapling mechanism is supplied with a suitable supply of material ready for use and that power is applied to the shaft 54 ready for use. Also assume that before the starting of the machine on this cycle of operation one or more staples have been driven in the left hand ends of the first or left hand cleats. The operator now takes hold of handle 58 moves it to the left thus throwing in clutch 56 and starting the machine. As soon as shaft 54 begins to rotate in a counter clockwise direction it drives arm 90 to the left this through the engagement of the pawls 112 with the ratchet teeth on wheel 110 rotating shaft 20 in a counter-clockwise direction. During this movement nothing of importance takes place in the machine except that the sprocket chains with the box material thereon are drawn to the left as far as the movement of the arm 90 can carry them, before the top 106 of cam 66 is reached, at which point brake mechanism 94-96 takes control of the shaft 26 and sharply stops it and consequently the sprocket chains and attached parts. As the high point 106 in cam 66 passes roller 92 the spring 120 begins to draw lever arm 90 and crosshead 130 to the right as viewed in Fig. 2, the sprocket chains and work thereon remaining stationary. This movement of these parts continues until, in the first instance, dog 152 engages notch 244 in plate 242 whereupon the crosshead is stopped. During this short movement of the crosshead and the continued movement of the main shaft before arm 90 begins to again move to the left a staple has been driven by the stapling mechanism 230 through the cleat and attached parts on each side of the machine. Nothing further happens in this part

ticular cycle of operations until the cam 66 begins to again drive lever 90 to the left when the operation is repeated. This cycle of operation is repeated over and over until 5 the right hand end of the first cleat is nearly reached when the pin 160 belonging to the push member 170 of that particular cleat assumes a position where it moves plate 242 out of the path of travel of dog 152 and pre- 10 vents the notch 244 on plate 252 affecting said dog 152, but on the other hand this pin 160 of the first push member 170 itself engages dog 152, perhaps at the point where notch 244 would have acted, perhaps at either 15 side of that point, and operates the ratchet key 142-145 to stop the crosshead in its movement to the right at exactly the right point so that the next staple driven will be at the correct point adjacent to the right 20 hand end of the first cleat shown at the left hand end of Fig. 1. The cam 106 or other fixed throw actuator, moves the driving pawl in its oscillating or reciprocating movement to a fixed extreme position in one direction, 25 but lost motion is provided for between the driving pawl and the cam or other actuator in the opposite direction. The rack 126 and its cooperating pawls 142 act as a positive stop to determine the amount of this 30 lost motion and fix the other extreme position of the actuator and thereby control the succeeding step of the work feeding mechanism. Members 160, which in the present instance are positioned on the feed chains, 35 are presented successively in correlation with the movement of the work, which is a particular instance of presentation governed by the relative position of the work and stapling mechanism at any particular moment. These 40 members act to bring the driver, through the medium of the connecting rod 138, into cooperating relationship with the stop and the position of the staples on the box blank is thus governed. Members 160 act merely 45 as trips in the present instance and the conveyor chains or other mechanism which carry them are not called upon to do any heavy work in positioning any of the driving mechanism, but the positioning is cared for by 50 the fixed abutments provided by the rack which absorb the shock of the checked moving parts. A continuance of the operation of the machine merely repeats the cycles of 55 operation just described applying them successively to the second, third and fourth cleats of the box material on the machine thus finally completing one complete box blank and carrying it to the left beyond the machine whereupon the first push member 60 of the next oncoming box drives its pin 180 against the arm 228 thus cutting the wires which connect the completed box blank with the rest of the device and if the cam 65 is present stopping the machine in the manner described.

During the revolution of shaft 54 in each cycle of operations described the arm 80 is manipulated by this shaft through the mechanism described to keep pushing the box sides up against the fingers 184 and 188, as 70 the case may be, thereby insuring their always being in proper position with reference to the cleats preparatory to stapling. As this mechanism keeps the box sides in order and as the spring members 234 keep 75 the cleats in proper position in the manner described, an accurately formed box blank is produced without any attention from the operator except to insert the crude material and carry away the completed box blank. 80

By this device it is possible to adjust the push members along the sprocket chains to take care of the formation of box blanks in which the successive sides of the box vary greatly in width and at the same time insure 85 accurate stapling of the parts together particularly insuring the placing of staples where they are most needed in close proximity to the corners of the box and without running any risk of idly driving staples 90 in the corners of the box as has heretofore frequently happened in prior devices.

It will be noticed that by reason of the fact that the cleats travel upon an independent track separate and apart from the 95 sprocket chains much greater accuracy is obtained than is possible where the weight of the cleat and box sides has to be carried by the chains, as in the prior art. In this device, boxes of different lengths as well as 100 different widths can readily be formed by simply varying the distance apart transversely of the machine of the cut-off and stapling mechanism which is readily effected by the construction shown and de- 105 scribed.

In this machine the use of the band brake 110 serves to take up all lost motion of the parts and insures the accurate operation of the machine in one direction while the cross 110 head device 130 with its attached parts, sometimes called the "shock absorber," performs the same function in stopping the parts which move in the opposite direction, these two mechanisms together insuring very 115 accurate operation of the machine and consequently very satisfactory product.

While the device here illustrated has been described as operating upon a wire bound box blank, it is perfectly obvious that it 120 may be used for attaching parts of a box together where no wire is used.

Having thus described my invention, what I claim as new and desire to secure by Letters Patent, is:

1. In a device of the class described, in combination with a suitable frame and a pair of conveyers traveling through the frame, a track in the frame adjacent to each conveyer in which box parts are adapted 125 130

- to travel, adjustable push members detachably secured to the conveyer, means upon each push member entering the track adjacent to it to engage a box part in said track for the purpose of driving it along the track as the conveyer moves, and another member extending from each push member adapted to engage and push a second box member placed upon the first mentioned box member pushed by that particular member, certain of the said second members extending from the push member being movably mounted upon the push member to allow for variations in width of the second kind of box members placed upon the machine.
2. In a device of the class described, in combination with a suitable frame and a pair of conveyers traveling through the frame, a track in the frame adjacent to each conveyer in which box parts are adapted to travel, adjustable push members detachably secured to the conveyer, means upon each push member entering the track adjacent to it to engage a box part in said track for the purpose of driving it along the track as the conveyer moves, another member extending from each push member adapted to engage and push a second box member placed upon the first mentioned box member pushed by that particular member, certain of the said second members extending from the push member being movably mounted upon the push member to allow for variations in width of the second kind of box members placed upon the machine, means for driving said conveyer member, and automatic means pushing the box members upon the machine in the direction of motion of the conveyer to thereby properly position them, for the purposes set forth.
3. In a machine of the class described, the combination of a conveyer, a movable driving member constructed and arranged to drive the conveyer selectively variable distances in a given direction, means for propelling the driving member, and an automatic brake device operated by said propelling means arranged to lock the conveyer in stationary position at the instant said driving member completes its movement of the conveyer.
4. A machine of the class described, comprising a conveyer, a reciprocable driving member, a mechanism arranged to detachably connect the driving member to the conveyer to drive the conveyer selectively variable distances in a given direction only, means for actuating the driving member, and a brake device for the conveyer operated by said actuating means at the moment the conveyer has reached the limit of its movement under the action of the driving member to instantly stop and lock the conveyer.
5. In a machine of the class described, a shaft, a wheel and a conveyer carried upon and moved by the wheel, a reciprocable driving mechanism adapted, when moved in one direction, to rotate the wheel and thus move the conveyer and adapted to leave the wheel and conveyer at rest when it moves in the opposite direction, a power driven device for actuating said driving mechanism, a brake wheel upon the shaft, a brake band upon said brake wheel, and levers connecting the opposite ends of the brake band to said driving mechanism, all of the parts being so proportioned that the brake band grips the brake wheel at the instant the conveyer reaches the limit of its movement under the action of the driving mechanism to positively stop it and at other times does not interfere with the device.
6. In a machine of the class described, an endless conveyer member movable through the machine, a source of power for driving the machine, means for detachably connecting said source of power to the conveyer to drive it, and a member selectively adjustable along the conveyer adapted to engage said connecting means as it is moved adjacent thereto and thereby disconnect the conveyer from the source of power without stopping the machine.
7. In a device of the class described, a conveyer member, means for driving the conveyer member, a source of power for actuating said driving means, a clutch between the last two mentioned elements, a cam device arranged, when moved, to disconnect the clutch thus shutting off the power and stopping the machine, a member carried by the conveyer adapted, at one point in the travel of the conveyer, to move the cam to so actuate the clutch, and means for selectively locating said last mentioned member at different points along the conveyer.
8. A machine of the class described comprising a conveyer, a reciprocable driving means adapted, in one direction of its motion, to drive the conveyer in that direction and adapted as it moves in the opposite direction to leave the conveyer at rest, members spaced along the conveyer arranged to be engaged by a part of said reciprocable driving means on its second or return stroke, and a shock absorbing device set in action by the last mentioned engagement of parts arranged to positively stop said return movement of the driving means.
9. A machine of the class described comprising a conveyer, a reciprocable driving means adapted, in one direction of its motion, to drive the conveyer in that direction and adapted as it moves in the opposite direction to leave the conveyer at rest, members spaced along the conveyer arranged to be engaged by a part of said reciprocable driving means on its second or return stroke, and a shock absorbing device comprising a rack and a plurality of ratchet dogs set in

action by the last mentioned engagement of parts arranged to positively stop said return movement of the driving means.

10. In a device of the class described, a shock absorbing device comprising a rack and a cross head movable one with reference to the other, a ratchet dog on the cross head, means urging the ratchet dogs into engagement with the rack, and a cam device normally holding the ratchet dog out of engagement with the rack but movable to a position such that the dog may engage the rack.
11. A machine of the class described comprising a stapling mechanism; a work holder; and means for relatively moving the work comprising a reciprocating driver having a fixed extreme position in one direction, a cyclically moving fixed throw actuator arranged for lost motion with respect to said driver, a non-traveling stop for said driver determining the amount of such lost motion, and means dependent in action upon the relative position of the work and the stapling mechanism operatively to connect said driver and stop.

12. A machine of the class described comprising a stapling mechanism; supporting means for box blank materials, and means for advancing box materials along said guides beneath said stapling mechanism including a reciprocating driver having a fixed extreme position and arranged to impart movement to said advancing means when moving in one direction, a non-traveling stop for determining the other extreme position of said driver, and means dependent in action on the position of the work relative to the stapling mechanism to bring stop and driver into coöperating relation.

13. A machine of the class described comprising a stapling mechanism; supporting means for box blank materials and means for advancing box materials along said guides beneath said stapling mechanism including a reciprocating driver having a fixed extreme position and arranged to impart movement to said advancing means when moving in one direction, a stop for determining the other extreme position of said driver, and trips arranged for successive action correlated with the movement of said conveyer to bring stop and driver into coöperating relation.

14. A machine of the class described comprising a stapling mechanism, a conveyer to advance box blank materials thereto, driving means to move said conveyer in successive steps, a member coöperating with said driving means to govern the length of those steps, and members distributed along the conveyer operatively to connect said member and said means.

15. A machine of the class described comprising a stapling mechanism, a conveyer to advance box blank materials thereto, driv-

ing means to move said conveyer in successive steps, a member coöperating with said driving means to govern the length of those steps, and members arranged for a successive presentation correlated with the movement of the conveyer and operating to connect said member and said means.

16. A machine of the class described comprising a stapling mechanism, a conveyer for presenting box materials thereto, a reciprocating driver having a fixed extreme position and arranged to drive said conveyer on movement in one direction, a stop for determining the other extreme position of said driver, and means dependent in action on the position of the conveyer relative to said mechanism to bring stop and driver into coöperating relation.

17. A machine of the class described comprising a stapling mechanism, a conveyer for presenting box materials thereto, a reciprocating driver having a fixed extreme position and arranged to drive said conveyer on movement in one direction, a stop for determining the other extreme position of said driver, and trips arranged for successive action correlated with the movement of said conveyer to bring stop and driver into coöperating relation.

18. In a machine of the class described, a conveyer member, a plurality of push members located upon the conveyer, a track adjacent to the conveyer for the passage of one sort of box parts, means upon each push member for positioning and driving one of said box parts, means also upon said push members for engaging and positioning a second kind of box parts placed over the first, means for intermittently driving the conveyer in a given direction, and means controlled by said push members for increasing or decreasing the length of certain movements of the conveyer, for the purposes set forth.

19. In a machine of the class described, provided with facilities for the passage therethrough of box cleats and box sides, a stapling device for securing these box parts and a wire together, a cut-off device for cutting the wire, means for controlling the stapling with reference to the passing box parts, and a clutch device through which power mechanism driving the machine may be cut off, a plurality of conveyer members extending through the machine and provided with a plurality of push members along their lengths, certain of which push members are constructed and arranged to position the cleats and the box sides and control said stapling operation, certain of which push members being arranged to control the cut off mechanism for the wire and certain others finally to control the automatic clutch.

20. A machine for use in making wire-

- bound boxes comprising, in combination, binding wire applying and fastener-setting mechanism; work-supporting means; means to cause relative progression between said fastener-setting mechanism and the work; and automatic means to locate fasteners at predetermined points comprising controlling members arranged along the work and mechanism successively controlled thereby, 5 having controllably interengageable members, for determining feed movements.
21. A machine for making wirebound boxes by the action of binding wire applying and fastener-setting mechanism upon 10 assembled box parts, comprising, in combination, said mechanism; work-supporting means; means to cause relative progression between said mechanism and the work; and automatic means to locate fasteners at predetermined points comprising successively 15 acting controlling members and mechanism controlled thereby, having members adapted to coöperate at different phases of the cycle of operation of the machine, for determining feed steps.
22. A machine of the class described comprising, in combination, fastener-setting mechanism; work-supporting means; means to cause relative progression between said 20 mechanism and the work; and automatic means to locate fasteners at predetermined points comprising successively acting controlling means correlated with selected relative positions of the work and fastener-setting mechanism, and mechanism controlled 25 thereby, having controllably interengaging members, for determining feed movements.
23. A machine of the class described comprising, in combination, fastener-setting 30 mechanism; work-supporting means; means to cause relative progression between said fastener-setting mechanism and the work; and automatic means to locate fasteners at predetermined points comprising controlling 35 members arranged along the work for successive presentation and a stop mechanism distinct from but controlled by said members for determining feed movements.
24. A machine of the class described comprising, in combination, fastener-setting 40 mechanism; work-supporting means; means to cause relative progression between said fastener-setting mechanism and the work; and automatic means to locate fasteners at predetermined points comprising controlling 45 members arranged along the work for successive presentation and a stop mechanism distinct from but controlled by said members for determining feed movements.
25. A machine of the class described comprising, in combination, fastener-setting 50 mechanism; work-supporting means; means to cause relative progression between said fastener-setting mechanism and the work; and automatic means to locate fasteners at predetermined points comprising a stop 55 mechanism having a stationary impact sustaining member for determining feed movements and successively acting devices correlated with selected relative positions of the work and fastener-applying mechanism for controlling effective operations of said stop mechanism.
26. A machine for use in making wirebound boxes by the action of binding wire applying and fastener-setting mechanism upon box materials comprising, in combination, 60 said mechanism; work-supporting means; step-feed mechanism whereby the work is progressively subjected to the action of the fastener-setting mechanism; an automatic step-feed adjuster including a pawl and rack; and controlling means therefor including successively active members correlated with selected relative positions 65 of the work and fastener-setting mechanism.
27. A machine of the class described comprising, in combination, coöperating fastener-applying, work-supporting and step-feed mechanisms for securing fasteners at intervals to box sections, an automatic step feed adjuster including a pawl and rack, and successively presented control means 70 therefor arranged along the work.
28. A machine of the class described comprising, in combination, fastener-setting mechanism; work-supporting means; regulable step-feed mechanism; and regulating mechanism therefor including controllably 75 inter-engageable members, normal control means therefor and successively substituting control means to determine certain feed steps.
29. A machine of the class described comprising, in combination, fastener-setting 80 mechanism; work-supporting means; step-feed mechanism having a variable stroke driver; a pawl-and-rack mechanism, one member of which is connected with said driver, and means controlling said pawl-and-rack mechanism to determine the stroke.
30. A machine of the class described comprising, in combination, a step-by-step fed 85 conveyer for feeding box sections; mechanism to fasten binding wire to said sections at intervals; stop mechanism independent of the conveyer for determining feed steps; and means automatically controlling said stop mechanism comprising successively 90 presented members moving with the conveyer.
31. A machine of the class described comprising, in combination, coöperating stapping, work feeding and binding wire supplying mechanism, and wire severing means comprising a wire cutter, a reciprocating cross head having means to actuate the same, a rotatable bar normally supporting 95 said cutter out of reach of said actuating means.

means, and automatic means to rotate said bar to bring the cutter within range of said actuating means.

32. A machine of the class described comprising, in combination, coöperating stapping, work feeding and binding wire supplying mechanism, and wire severing means comprising a plunger and cutter adapted to be actuated thereby, reciprocating means to 10 actuate the plunger, a rotatable bar normally supporting said plunger and cutter

in inoperative position, and automatic means to move said bar to bring the cutter to operative position, and the cutter within its actuating means.

In witness whereof, I have hereunto subscribed my name in the presence of two witnesses.
